DESIGN.

F. MANKEY.

OPEN WORK PANEL.

No. 16,461.

Patented Jan. 12, 1886.

UNITED STATES PATENT OFFICE.

FREDERICK MANKEY, OF WILLIAMSPORT, PENNSYLVANIA.

DESIGN FOR AN OPEN-WORK PANEL.

SPECIFICATION forming part of Design No. 16,461, dated January 12, 1886.

Application filed November 13, 1885. Serial No. 182,768. Term of patent 7 years.

To all whom it may concern:

Be it known that I, FREDERICK MANKEY, of Williamsport, Lycoming county, Pennsylvania, have invented and produced a new and original Design for Open-Work Panels, of which the following is a specification, reference being had to the accompanying photograph, forming part hereof.

Upon the face of the panel appear rectangular elevations A, arranged in rows, the elevations in each row being separated by channels B, and the several rows being separated by channels C. The upper edges of said elevations are beveled or inclined. In the center of each elevation, and extending through the panel, is an opening of octagonal form,

having four straight sides, D E F G, and four inwardly-convex sides, H I J K. The convex or curved sides alternate with the straight sides.

I claim—

The design for an open-work panel, substantially as herein shown and described, which consists in the quadrangular elevations A, arranged in rows, with intermediate channels, B C, and the hexagonal openings D E F G H I J K, extending through said elevations.

FREDERICK MANKEY.
